UNITED STATES PATENT OFFICE.

CARL VOIGT BODOM, OF TAMPICO, MEXICO.

FASTENING DEVICE FOR LIFEBOATS.

1,349,317.

Specification of Letters Patent. Patented Aug. 10, 1920.

Application filed May 4, 1920. Serial No. 378,747.

To all whom it may concern:

Be it known that I, CARL VOIGT BODOM, a subject of the King of Norway, residing at Tampico, Mexico, have invented certain

5 new and useful Improvements in Fastening Devices for Lifeboats; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 The present invention has for its object a device for securing life-boats to the deck, and the object of the invention is to provide an arrangement whereby it is possible to make the boat ready for use in the short-

20 est possible time. The arrangement according to the invention comprises two or more stools or blocks gripping the keel of the boat and being fastened on horizontal rotatable cross shafts under the boat. Fur-

25 ther the arrangement comprises arms fastened to said cross shafts, said arms being adapted to be connected with hooks gripping the gun-wales of the life-boat. The connection between the said hooks and arms 30 comprises a pelican-hook or the like, so that it may be easily loosened.

When the arms are disconnected from the hooks and swung down toward the deck, the stools are simultaneously brought out 35 of engagement with the boat keel and the boat is free.

In the accompanying drawing:

Figure 1 is a side view of one form of the invention.

40 Fig. 2 is an end view and

Fig. 3 is a detail view of one of the stools.

The arrangement comprises two cast iron stools or blocks A fastened on shafts B,

which are mounted in bearings C on the deck. On their inner ends shafts B are provided with arms D serving as turning handles for the shafts and at the same time adapted to be connected with hook chains E. 45

The stools A are provided at the top with grooves F fitting about the boat keel G and 50 are slightly rounded at one side.

The arms D are provided at their upper end with a pelican-hook H adapted to be maintained in locking position by means of ring K. The pelican-hook H serves to connect arm D with chain E, to the free 55 end of which is fastened hook M.

The fastening chains L for the outside gun-wale of the life-boat are provided in the usual manner with counterthread bolts 60 for stretching the same.

When the boat is to be lowered, the ring K is pulled down, thereby disconnecting arm D from chain E, whereupon arms D with the stools A are swung down and the boat 65 is free. The outside fastening chains may be slipped off by tilting the boat now hanging in the ropes.

I claim:—

In a fastening device for life boats, stools 70 for gripping the keel of the boat, rotatable cross shafts on which said stools are mounted, radial arms at the inner ends of said shafts, hooks for gripping the gun-wale of the boat, and means comprising a pelican- 75 hook for connecting the aforementioned hooks with the free ends of said arms when the same are in a vertical position.

In testimony that I claim the foregoing as my invention, I have signed my name in 80 presence of two subscribing witnesses.

CARL VOIGT BODOM.
